CASSEROLE OR SIMILAR ARTICLE

Frank J. Benes, Lancaster, Ohio, assignor to Anchor Hocking Glass Corporation, Lancaster, Ohio, a corporation of Delaware

Original design application Dec. 6, 1966, Ser. No. 4,928. Divided and this application July 12, 1967, Ser. No. 8,201

Term of patent 14 years

(Cl. D44—15)

FIG. 1 is a perspective view of the design of a casserole or similar article showing the present invention;

FIG. 2 is a top view thereof;

FIG. 3 is a side view thereof;

FIG. 4 is an end view thereof;

FIG. 5 is a sectional view taken along line 5—5 of FIG. 3.

The characteristic features of the design reside in the combination on a casserole of the configuration shown of handles of the proportions shown which are downwardly curved and an upper body portion of the casserole being slightly tapered and the lower body portion having a greater taper.

The present application is a division of my copending design application Ser. No. 4,928, filed Dec. 6, 1966.

I claim:

The ornamental design for a casserole or similar article, substantially as shown and described.
